UNITED STATES PATENT OFFICE.

ROBERT G. FLEMING, OF SAN JOSE, CALIFORNIA.

CAR-UNLOADER.

1,213,177.

Specification of Letters Patent.

Patented Jan. 23, 1917.

Application filed December 2, 1915. Serial No. 64,767.

To all whom it may concern:

Be it known that I, ROBERT G. FLEMING, a citizen of the United States, and resident of San Jose, in the county of Santa Clara and State of California, have invented certain new and useful Improvements in Car-Unloaders, of which the following is a specification.

My invention relates to a machine for unloading flat cars or gondolas. At present, as is well known, flat cars or gondolas loaded with sand, gravel, broken stone or other material in condition for shoveling are unloaded almost entirely by manual labor.

It is the main object of my present invention to obviate the necessity of employing bodies of men for this purpose by constructing a power driven machine which can be positioned over a car and caused to rapidly and effectively empty the same.

Other objects are to provide a mechanism of the character indicated that can be adjusted longitudinally of a car, that is adapted for use with any height of car, that can be transferred from one carrier to another, that can be disassembled for transportation, and that can be used for unloading cars of any width.

Further objects and advantages will appear in the following description and in the accompanying drawings in which,

Figure 1 is a rear elevation of my machine in position. Fig. 2 is a plan view of the same. Fig. 3 is a side elevation of the same. Fig. 4 is a detail perspective of the top elevator sprocket in position, parts being broken away. Fig. 5 is a detail elevation showing the rollers on the lower bar of elevator carrying frame, parts being broken away. Fig. 6 is a perspective view of the elevator tilting and shifting mechanisms, parts being broken away. Fig. 7 is a perspective view of one method used for raising and lowering the framework of my machine, parts broken away. Fig. 8 is a detail perspective showing the method of securing the frame to the car, parts broken away. Fig. 9 is a detail perspective showing a method of joining the upper and lower parts of the framework, parts broken away. Fig. 10 is a detail perspective showing a preferred form of carrying belt, parts being broken away.

Similar characters of reference refer to similar parts throughout the several views.

Referring now more particularly to the drawings, the carrier consists of a truck 1 mounted on track 2 and driven by engine 3 in the customary manner with high and low speed connections and reversing mechanisms.

The framework in which the operating parts of my invention are mounted consists of a standard 4 suitably braced and removably attached to truck 1 as indicated in Fig. 8, in which 5 indicates one of the legs of said support secured to bracket 6 by bolts 7, bracket 6 being secured to the upper surface of truck 1 by bolts 8. Cantaliver arm 9 consists of two similar, parallel alined sides 10 and 11 rigidly fastened together by suitable cross bars and braces as 12 and 13 and is removably secured to the upper end of support 4 by bolts as indicated at 14, and is suitably balanced and braced to withstand the stresses and strains to which it may be subjected.

Rigidly mounted on the top of cantaliver arm 9, spaced a distance apart greater than the width of the widest car to be unloaded and projecting over the side of the projecting portion of said arm 9 are two brackets 15 and 16 respectively, provided with bearings 17 in which shaft 18 revolves, and connected by beam 15^a.

A conveyer belt 19 is shown operated by rollers 20 and 21 mounted in bearings 22 and 23 respectively in cantaliver arm 9, bearings 23 being adjustable in order to permit taking up the slack in belt 19 as indicated at 23^a. Idler 24 is mounted in arm 9 in such a manner as to raise the lower half of belt 19 and keep the same free from the framework and working parts of the machine, and idlers 24^a are inserted to give 95 additional support to the upper half of belt 19. A sprocket is indicated at 25 rigidly secured to the shaft of roller 20 and is driven as hereinafter described. Shaft 18 has a sprocket 26 rigidly secured thereto and is square throughout a portion of its length as indicated at A, this distance A representing the limit of transverse adjustment of elevator frame 27, and is made square so that the elevating parts may be 100 driven by shaft 18 and at the same time permit the adjustment above referred to. The elevator frame 27 is preferably made as indicated in Figs. 1, 2 and 3, properly braced and provided with bearings 29 and 30. Collar 31 is mounted so as to revolve in bearings 29, said collar 31 being adapted 110

to slidably engage the square portion of shaft 18. Rigidly secured to collar 31 is sprocket 32 carrying endless chain 33 which in turn carries buckets 34. At the lower end of frame 27 is revolubly mounted sprocket 35 on shaft 36 revolving in bearings 30, said sprocket 35 also engaging endless chain 33. Elevator frame 27 is of such a length that when in a perpendicular position it is adapted for use in the lowest cars; therefore when a higher car is to be unloaded means must be provided by which the elevator can be operated at such an angle, as at 28, as to just clear the floor of said car. To accomplish this I provide a tilting mechanism as follows: Bearings 17 are provided with hubs 37 upon which are revolubly mounted bars 38, said bars 38 being connected at their free ends by bars 39 and 39^a passing through the elevator frame as shown. Pivotaly attached to bars 38, and near the lower ends thereof, by bolts 40, are ratchets 41, the same resting on supports as 42 secured rigidly to side 10 of arm 9. Engaging ratchets 41 are gears 43 keyed to shaft 44 mounted on arm 9 in approximately the position indicated in Figs. 1, 2 and 3, and having a gear 45 keyed to one end thereof driven by worm 46. Worm 46 is operated by shaft 47 and hand wheel 48; therefore when hand wheel 48 is operated the elevator frame 27 will be forced outwardly or inwardly as the case may be, with shaft 18 as a pivot. Rollers 49, 50 and 51 are revolubly mounted in frame 27 in such a manner as to engage bar 39, and rollers 49^a and 50^a are mounted in frame 27 in such a manner as to engage bar 39^a and thus permit the free transverse movement of elevator frame 27 irrespective of the angle at which it might be positioned. This transverse adjustment is effected by means of the cables 52 and 52^a secured to elevator frame 27 by suitable fastenings as 53 and 53^a, and the cables are operated by the following mechanism: At 54 is a hand wheel operating shaft 54^a and worm 54^b, which in turn operate gear 54^c. Gear 54^c operates sprocket 54^d on shaft 54^e and thereby drives chain 54^e operating on sprocket 55 which runs idly upon shaft 18. To sprocket 55 is secured bevel gear 56 which meshes with bevel gear 57 mounted on vertical shaft 58 which is held in position by bearings 59 secured to one bar 38, and step 60 on bar 39. Secured to shaft 58 are scored wheels 61 and 61^a, and secured to the opposite bar 38 are scored pulleys 62 and 63. By means of this mechanism elevator frame 27 may be shifted from one side of the car to the other by turning hand wheel 54, sprocket 55 running loosely on shaft 18 permitting this adjustment to be made regardless of the angle to which the elevator frame 27, and of course bars 38, may be positioned.

At 64 is shown a shaft mounted in bearings 65 secured to standard 4. At 66 is a sprocket keyed to shaft 64 and driven by engine 3 by means of chain 67. At 68 is shown a shaft mounted in bearings 69 positioned in arm 9 in approximately the position shown and driven by sprocket 70 keyed thereto, chain 71 and sprocket 72 keyed to shaft 64.

73 indicates a shaft at right angles to shaft 68, mounted in bearings 74 and having gears 75 and 76 and sprocket 77 keyed thereto, said shaft 73 being driven by bevel gear 76 meshing with bevel gear 78 keyed to shaft 68. Chain 79 connects sprocket 77 with sprocket 25 which completes the mechanism for driving belt 19. A sprocket 80 keyed to shaft 81 mounted in bearings 82 is connected to sprocket 26 by chain 83 and is driven by a bevel gear 81^a keyed to said shaft 81 and in mesh with bevel gear 75, thus providing the driving mechanism for shaft 18 and the parts secured thereto.

By the above description it may be seen that the conveyer and elevator are operated simultaneously and at predetermined relative speeds from main shaft 64, the power being applied by means of any ordinary clutch mechanism operated by a lever as 84.

At 85 are indicated guards which prevent material from being thrown beyond the conveyer when the elevator is in operation.

As it is sometimes desirable to swing arm 9 and elevator frame 27 clear of the main track, a curve is provided at each end of the track 2 upon which truck 1 travels in order that said truck can be driven in either direction around a curve and so swing arm 9 clear of the main track.

Inasmuch as a flat carrier belt would not retain all of the load placed upon it a conveyer having sloping sides as shown at 92 will usually be used.

Having thus described my invention, what I claim as new and desire to secure by Letters Patent, is:—

1. In a car unloader, the combination with a support, an arm extending from said support, a conveyer operatively positioned in said arm, an elevator operatively attached to said arm and longitudinally adjustable with relation thereto and pivotally adjustable in a plane perpendicular to said arm, of means for effecting said longitudinal adjustment, said means comprising a pivotally mounted frame adapted to move with said elevator in the pivotal adjustment thereof, one or more cables attached to said elevator and operating over pulleys attached to one side of said frame and pulleys mounted on a shaft positioned near the opposite end of said frame, and means for manually operating said shaft.

2. In a car unloader, the combination of a support, an arm extending from said sup-

port, a conveyer operatively positioned in said arm, an elevator operatively attached to said arm and longitudinally adjustable with relation thereto and pivotally adjustable in a plane perpendicular to said arm, a pair of auxiliary arms positioned at right angles to said arm, a shaft operatively positioned in said auxiliary arms and having driving means connected thereto, a frame 5 pivotally mounted on said shaft and adapted to move with said elevator in the pivotal adjustment thereof, means for pivotally ad-

justing said frame and said elevator, and means for longitudinally adjusting said elevator in said frame, said elevator being pivotally mounted on said shaft and being provided with a plurality of rollers adapted to engage the top of said frame and a plurality of rollers adapted to engage the bottom of said frame. 15

In testimony whereof I have hereunto affixed my signature this 22nd day of November, 1915.

ROBERT G. FLEMING.
